CLAIM

The ornamental design for a control panel for a combined vehicular radio receiver and digital clock, as shown and described.

DESCRIPTION

FIG. 1 is a front, top and left side perspective view of a control panel for a combined vehicular radio receiver and digital clock;

FIG. 2 is a top plan view thereof;

FIG. 3 is a front elevational view thereof;

FIG. 4 is a left-side elevational view thereof;

FIG. 5 is a right side elevational view thereof; and,

FIG. 6 is a bottom plan view thereof.

The broken line showing of the housing in the drawing figures is for illustrative purposes only and forms no part of the claimed design.

FIG.4

FIG.5

FIG.6
